(57) **CLAIM**

The ornamental design for a trading card autograph holder, as shown and described.

DESCRIPTION

FIG. 1 is a perspective view of a trading card autograph holder.

FIG. 2 is a front view of the trading card autograph holder.

FIG. 3 is a rear view of the trading card autograph holder.

FIG. 4 is a right side view of the trading card autograph holder, of which the left side view is a mirror image.

FIG. 5 is a top view of the trading card autograph holder; and,

FIG. 6 is a bottom view of the trading card autograph holder. The broken lines showing pens are environmental while all other broken lines illustrate portions of the trading card autograph holder and form no part of the claimed design. The contour lines and surface shading illustrate the underlying contours and are not surface ornamentation.
